UNITED STATES PATENT OFFICE.

SAMUEL C. STEARNS, OF DETROIT, MICHIGAN, ASSIGNOR TO THE FREDERICK STEARNS & COMPANY, OF SAME PLACE.

DESIGN FOR A SYRINGE.

SPECIFICATION forming part of Design No. 32,637, dated May 8, 1900.

Application filed April 11, 1900. Serial No. 12,485. Term of patent 14 years.

To all whom it may concern:

Be it known that I, SAMUEL C. STEARNS, a citizen of the United States, residing at Detroit, in the county of Wayne and State of Michigan, have invented and produced a certain new and original Design for Syringes, of which the following is a specification, reference being had therein to the accompanying drawing, in which the figure is an elevation 10 of the syringe.

The central portion or body A of the syringe is bulb-shaped in configuration, and said body is elongated at its ends, forming two oppositely-extending cylindrical stems B B', 15 which terminate, as shown, in cylindrical enlargements C C', respectively. The enlargement C' terminates in a bulb D, while from the complementary enlargement extends the

needle E, having, as shown, a conical portion F, constituting the head, and the reduced cylindrical portion G, as shown. 20

The essential feature of my design consists of the bulb-shaped syringe-body, having reduced cylindrical end portions or stems terminating in cylindrical enlargements, and the 25 bulb and needle extending from the enlargements, as shown.

What I claim as my invention is—

The design for syringe, substantially as herein shown and described. 30

In testimony whereof I affix my signature in presence of two witnesses.

SAMUEL C. STEARNS.
